UNITED STATES PATENT OFFICE.

JOHN S. THOMPSON, OF CHICAGO, ILLINOIS.

STRIP-CASTING MACHINE.

1,423,474.

Specification of Letters Patent. Patented July 18, 1922.

Application filed November 20, 1920. Serial No. 425,363.

To all whom it may concern:

Be it known that I, JOHN S. THOMPSON, a citizen of the United States, residing at Chicago, in the county of Cook and State 5 of Illinois, have invented certain new and useful Improvements in Strip-Casting Machines, of which the following is a specification.

The invention relates to improvements in 10 machines for intermittently casting a continuous strip of material in fused integral sections.

An object of the invention is the provision of a machine for casting a continuous 15 strip of material in intermittently formed sections in progressive order, moving the strip, and cutting and trimming the strip into definite lengths during the intermission between the strip moving operations.

Another object is to provide a machine 20 in which molten metal is injected into a molding chamber; the chamber is then reciprocated with the strip and returned 25 without it to advance the section of the strip cast during the previous operation, in which the movement of molten and cast metal is always in the same direction, and in which a space is provided in the molding 30 chamber for introduction of molten metal in the rear of the preceding cast section, for casting a succeeding section.

Another object is the provision of a machine 35 having a melting pot with a nozzle communicating therewith and a choker valve adapted to open and close the valve port through said nozzle; a pump for forcing the metal from the pot through the nozzle, in timed intervals, into a reciprocatory molding 40 chamber normally open at both ends, one end of which is closed by the nozzle, the axis of which is in alignment therewith, the opposite end being closed by a previously 45 cast section of the strip, and means for forcibly injecting molten metal into the molding chamber and causing it to fuse to the previously cast section and thereafter moving the molding chamber and the cast material in a direction away from the pot; 50 holding the cast strip to prevent its return movement; returning the molding block to its original position and repeating the cycle of operation.

Another important object of this inven-

tion is the provision for severing the cast 55 strip into definite lengths of exact dimensions.

Heretofore in machines of this class, a single knife or shear has been employed, which is brought into action after a predetermined number of sections has been cast, or else operated by the advancing strip of material coming into contact with an actuating finger. Either method has resulted in the severed material varying in length, due 60 to varying frictional resistances, and it is frequently necessary to trim the severed material by a separate mechanism to reduce it to exact lengths.

This difficulty is obviated in the present 70 mechanism by the provision of a trimming element operated in unison with the cutting device to simultaneously reduce the material to exact lengths.

Other, further and more specific objects 75 of the invention will become readily apparent, to persons versed in the art, from a consideration of the following description when taken in conjunction with the accompanying drawings forming a part hereof, 80 wherein:—

Fig. 1 is a side elevation of the machine showing some parts in section.

Fig. 2 is a transverse section taken on line 2—2 of Fig. 1.

Fig. 3 is a section taken on line 3—3 of Fig. 2.

Fig. 4 is an enlarged plan view of an adjustable means for determining the length of the strip or rule to be cut and trimmed 90 from a continuous strip.

Fig. 4^a is a fragmentary view of the controlling lever in another position.

Fig. 5 is a section through an elevation of a part of the machine taken on line 5—5 of 95 Fig. 4.

Fig. 5^a is a fragment of the stationary cutting knife.

Fig. 6 is a section detail, taken on line 6—6 of Fig. 5.

Fig. 6^a is a broken away portion of a vertically reciprocating rod, shown in Fig. 5 and Fig. 6, and a plan view in Fig. 4.

Fig. 7 is an isometric perspective view of the block enclosing the molding chamber in 105 which the strip is cast.

Fig. 8 is a plan view of the same.

Fig. 9 is a side elevation thereof.

Fig. 10 is a detachable block or part for holding the matrices shown in Fig. 12, to be secured to the part 7 by screws, or the like.

Fig. 11 is the carriage for holding the 5 mold block shown in Figs. 7 to 10, inclusive, and with which it is reciprocative.

Fig. 12 shows three pieces of a matrix, the edges of which form a boundary wall of the chamber in which the strip is cast.

10 Fig. 13 is a section of the mold block showing the parts assembled in the carriage.

Fig. 14 is an isometric perspective view of one-half of the guide box or housing in which the mold block is reciprocative.

15 Fig. 15 is a section taken on line 15—15 of Fig. 1.

Fig. 16 is a view taken at right angles to Fig. 15.

20 Fig. 17 is an enlarged sectional view taken on line 17—17 of Fig. 4.

Fig. 18 is a diagrammatic representation of a chart showing the timed relation of the moving parts of the machine.

25 In all of the views the same reference characters are employed to indicate similar parts.

The machine is intended, more particularly, for casting continuous lengths of printers' rules, leads and the like, in which 30 the strip is cast in relatively short sections intermittently, a subsequently cast section being fused to the section previously cast, so as to form a continuous strip of substantially unlimited length; the section previously 35 cast being moved with the mold block and held while the mold block is being returned for the purpose of casting another section. The machine is so arranged that the strip is severed in suitable lengths and, 40 trimmed in definite lengths, automatically, while the other operations are progressing.

In the chosen embodiment for disclosing my invention I have shown a side elevation of the machine in which 20 is the bed of 45 the machine and 21 and 22 are the legs upon which it is mounted. A rotatable shaft 23 finds bearings 24 and 25 on the respective ends of the machine. The shaft is rotatable by the hand lever 26 or furnished with a 50 suitable source of power not shown. Mounted on the front end of the bed 20 is a metal melting pot 27. The pot 27 is supported by the brackets 28 and 29, secured to the upper face of the bed, and under the pot and within 55 the bed 20, is located a gas burner 30, supplied with fuel by the pipe 31, for heating the pot and melting the metal therein.

In the interior body part 32 of the pot 27 is a cylinder 33 in which a plunger 34 is 60 reciprocative. The cylinder communicates with a well or sump 35 to contain metal to be forced into the molding chamber through which the strip to be cast passes, in a manner hereafter to be described.

65 A vertical rod 36 is attached to the upper

end of the plunger 34 and is connected to a horizontal two-ended lever 37, 39 which is pivoted, at 38, and which is connected at 41 to a vertical rod 40.

A cam 67 is secured to the shaft 23 and a 70 cam roller 42 is the means by which the plunger 34 is reciprocated, in a vertical path when the shaft 23 is rotated.

A spring 43 is connected to the leg 22, as at 44, and is the means for yieldingly 75 holding the cam roller 42 in contact with the cam 67. The horizontal lever 37 may be connected to the stem 36 through either one of the holes 45 for the purpose of reciprocating the plunger 34.

80 A nozzle 46 enters a cup shaped opening in the side wall of the pot 27, and is provided with a rounded terminal end 48 that fits in the cup in the relatively stationary plate 49, the plate being perforated, as at 85 50, to provide a port for the valve 51. A reciprocative valve 51 is adapted to close the port or orifice 50, in the nozzle plate 49. The valve 51 is prolonged into a valve stem 52, which finds bearings in the part 53, and which is reciprocative by a bell-crank lever 90 54. The stem 52 is provided with spiral flutes 55, through which the metal can pass between the stem and the part 56 in which the valve stem is reciprocative without disturbing the bearing for the stem.

The bell-crank lever 54 is pivoted to a stationary part 57 and extends rearwardly into a pronged end 58. A horizontal lever 59 is pivoted, as at 60, to the upper edge of 100 the pot 27, and has an end 61 that extends between the prongs 58 of the lever 54. The outer end, 62, is pivotally connected, as at 63, to a vertical rod 64. A roller 65 on the rod 64 projects into a cam-way, as at 105 66, in the side face of the cam 67 which is secured to the rotary shaft 23, so that when the shaft 23 is rotated the valve 51 is reciprocated by the mechanism described.

The spring 68, surrounding the vertical rod 110 64, yieldingly holds the valve 51 on its seat in the port 50 provided in the nozzle plate 49, there being sufficient clearance between the roller 65 on the vertical rod 64 and the cam in which it is contained so that the 115 valve 51 will always firmly close the opening, or port, in the plate 49 at times when such port should be closed.

A head 70 is secured to the bed 20 by 120 screws 71, or the like. The head 70 is provided with an overhanging ledge 72, under which is located the mold block housing, which consists of two members: 74 and 75. Each of these members is provided with a vertical wall 76 and spaced apart lateral or 125 horizontal walls 77 above, and 78 below. The edges of the walls are provided with grooves 79, an insertable feather or strip being used for the purpose of holding the members 74 and 75 in perfect register. The 130

members 74 and 75 of the housing are held together by screws 83 that pass through holes 84 in the member 74 and into threaded holes that register therewith in the box member 75. The member 75 is undercut, as at 85, to receive the guide member 86, that extends laterally of the carriage 87. The carriage 87 is provided with upwardly turned flanges 107—108, between which the 10 molding block 90 is adapted to be mounted. A channel 89 is formed in one face of the block to form a molding chamber therein, the wall 88 of the housing member 75 forms the opposite side of the molding chamber, 15 when the parts are assembled, as in Fig. 2. The width of the laterally extending ledges 91 and 92, determines the thickness of the strip or rule to be cast. When rules are to be cast, the forward end of the mold block 20 90 is cut away, as at 96, to receive the matrix holding replaceable block 97. This block is shown in the position it occupies with reference to block 90, in Fig. 13, the matrix being secured to the block 97 for the purpose of 25 giving one edge of the strip to be cast a desired configuration. In Fig. 12 the matrix is shown to consist of plates 98, 99 and 100 held in place by a screw threaded plate 101, by screws 102 that pass through the block 30 97 into the plate 101. The lower edges of the plates 98, 99 and 100 are of such configuration as to give the rule, cast by the machine, parallel printing lines on one of its edges. The screws 102 pass through the 35 holes 103 into the threaded holes 104 of the block 101 and screws 105 pass through holes 106 in the block 97 to hold the latter in place on the block 90. Of course, the shape and configuration of the matrix plates 98 to 100, 40 inclusive, may be changed to suit the character of face the rule cast in the machine is to possess.

The reciprocating carriage 87 receives the mold block 90 and is reciprocated in the 45 housing 74—75 by means of a pivoted lever 109, the end 109^a of which projects into the opening 110 of the carriage through the opening 111 provided in the housing 76. The lever 109 is pivoted to a laterally adjustable pivot at 112, adjustable for the purpose of changing the length of the stroke of the upper end 109^a of the lever 109. The lower end is provided with a roller 114, having a laterally projecting bearing 115 that 50 projects into a race-way 116 of the cam 117. The cam 117 is secured to the shaft 23 and rotates therewith. The race-way or groove 116 of the cam 117 is obliquely positioned as to its axis and therefore it is manifest that 55 when the cam is rotated the lever 109 will be reciprocated to a greater or less extent and thereby the mold block 90 in the housing 74—75 is reciprocated.

More or less lost motion is permitted for 60 the pivot 112 of the lever 109, so as to change

the effective length of stroke or extent of movement of the upper end of the lever. The greater amount of lost motion the less will be the movement of the upper end of the lever. The lever 109 has two arms 109^a 70 and 109^b. The arms 109^a and 109^b of the lever 109 are pivoted to a reciprocating bar 118, which is slidably movable in guides 119 and 120. The guide 120 is provided with a rectangular slot 121 to receive an axially adjustable wedge 122. The guide 119 is provided with a wedge-shape slot 123 to receive the wedge 122 and with a circular perforation to receive the end 124 of the wedge as a guide and permit the same to pass freely 80 therethrough. The other end of the wedge 122 is screw threaded and passes through the vertical wall of the bed 20. The wedge 122 is axially adjustable by the hand wheel 126. The sliding bar 118 is provided with an 85 opening 127 in which the wedge 122 may enter. When its widest part 122 is in the slot 121, with the wedge filling the slot 127, then the bar 118 is not axially movable and the upper end 109^a of the lever 109 has its 90 maximum movement. If the wedge, however, is withdrawn, as shown in Fig. 3, to a greater or less extent, then there is more or less lost motion provided to the pivotal point 112 by the opening 127 in the sliding 95 bar, and before the lever 109 will move on the pivot, the bar 118 will be moved back bodily until the boundary of the slot therein touches the wedge 122, whereupon the upper end 109^a of the lever 109, will then move, 100 which operation will have the effect of reciprocating the mold block 90 and the carriage 87 in the housing 74—75. The bar 118 is preferably provided with a screw 128, which may be used for adjusting the limit 105 of movement of the bar in one direction, while the wedge 122 adjusts the limit of its movement in the other direction. The adjustment of the wedge 122 will determine the length of the section of the strip or rule 110 to be cast, at each casting operation, or more correctly speaking, the length of strip to be extruded from the molding block subsequent to each casting operation.

A removable pin 129 holds the pivot pin 112 in place. When it is desirable to remove the mold block 90, bodily, from the housing 74—75, it is necessary that the upper end 109^a, of the lever 109, shall be taken from the slots 110 and 111. This is accomplished by lowering the lever. To lower the lever the pin 129 is removed, whereupon the pivot pin 112 is taken out and therefore the lever will move downwardly. Now it is not desirable that the lever should move down so far as to be 120 entirely displaced and therefore a pin 130 projects from the inner surface of the arm 109^b and rests upon the top of the reciprocating bar 118, when the upper end of the lever is in its lowermost position. This is a 125 130

matter of convenience for the purpose of retaining the lever 109 in approximately its operative position when the mold block 90 is to be changed. A stop pin 131 is passed through the outer end of the bar 118 to prevent its removal.

It may now be well to describe the mode of operation in casting the successive sections of the strip 95.

10 A section of previously cast material is inserted into the molding chamber 89 to close the end thereof opposite the nozzle plate 49, leaving a space between the face of the nozzle and the end of the material for the injection of molten metal, the end 134 of the mold block 90 being held tightly against the face of the nozzle plate 49 as shown in Fig. 1.

Assuming that the well or sump 35 in the melting pot 27 is filled with molten metal, 20 the cam 67 is so timed that when the shaft 23 is rotated the pump plunger 34 in the cylinder 33 will be depressed, thereby forcing the molten metal through the conduit 27' from the well 35 to the interior of the nozzle 46. A shoulder 46' on the valve 51 closes the orifice leading into the pot 27 when the valve port 50 is entirely opened by the retraction of the valve and therefore the metal will pass from the conduit 27' through the 25 nozzle and out through the port 50 provided in the plate 49, into the space 89 of the mold block 90, which is shown to be filled with the strip 95 in Fig. 2. The metal will enter the end 134 of the mold block 90 immediately 30 above the shoulder 135 provided therein. The shoulder 135 is used for the purpose of a driving means for the section of the strip that has been cast when the block 90, with the carriage 87, is reciprocated by the end 40 109^a of the lever 109.

If the block 97 is in place, in the cut-away part 96 of the block 90, and the matrices shown in Fig. 12 are secured to the block 97, as shown in Fig. 13, then the rule to be cast, 45 in the operation of the device, will be provided with two printing lines, the parts shown in Fig. 12 serving as the matrix for this purpose. If plain leads or slugs without a printing face are to be cast, the mold block 90 will be provided with a channel 89 formed throughout its entire length and of a suitable height between the shoulders 91-92 to produce the desired height of material.

50 The molten metal injected into the chamber 89 fuses to the end of the strip previously cast and forms therewith an integral casting, which strip may thereafter be divided into desired lengths.

60 The member 75, of the housing, is provided with a path for the circulation of cold water for the purpose of chilling the wall 88 near the strip 95 and carrying away the heat as the molten metal is injected into the mold block. Nipples 136' and 137' are provided,

to which a hose conveying water may be secured for circulating water through the member 75. After the molten metal has been injected into the mold block, the block is moved by the operation of the cam 117 70 leaving a space behind it in the housing 74-75.

Before the mold block has been reciprocated to the left, in viewing Fig. 1, the valve 51 is closed by the vertical rod 64 connected 75 to the horizontal lever 62, and by assistance of the open helical spring 68. As soon as the valve 51 is closed, the plunger 34 is raised to substantially the position shown in Fig. 1. This operation produces a partial vacuum in 80 the well 35 and causes the molten metal to pass through the flutes 55 of the valve stem 52 into the conduit 27' and then into the well 35, thus receiving another charge of metal 85 in the well 35, to be injected into the mold block when the piston is again caused to be moved into its lowermost position.

When the mold block 90 is moved outwardly, the metal strip that has previously been cast is seized by holding devices so that 90 the mold block is moved back into its operative position without carrying the strip with it. The means for holding the strip will now be described.

In the rear end face of the cam structure 95 117 (Fig. 2) is a cam-race or groove 136, in which a roller 137 is contained. A vertically reciprocating rod 138 has connected thereto a side member 139 providing a leg 140. Another leg 141 is provided by the vertically 100 reciprocating rod 138, leaving a space 142 between the two legs in which is contained the rotatable shaft 23. Now, inasmuch as the cam-race 136 is eccentric to the axis of the cam member 117, it is manifest that when 105 shaft 23 is rotated that the rod 138 will have a vertical up and down movement, produced by the cam.

Secured to the rod 138 is a bracket 143 (Figs. 15 and 16) which carries a vertically 110 slidable rod 144, axially adjustable in the bracket by means of a set screw 145.

On the side face of the housing 75 is secured a relatively small head 147 fastened to the housing by screws 148. To the head 115 147 is pivoted a clamping member 149 by means of the screw 150. The strip or rule clamping member is provided with an edge 151 and an extended end 152. Bearing upon the upper edge of the extended end 152 is a reciprocative plug 153, hollow in its upper 120 end and containing an open helical spring 154, the strength of which is adjusted by means of the screw 155, which is held in adjusted position by the nut 156. A dog 157 125 provided with a down-turned end 158 and a flat face 159 confronting the edge of the rule 95 is the cooperating clamping member. It is also provided with a horizontal shank member 160 that passes through a clamp 130

161, controlled by a screw and lever 162, and into an opening 163 in the head 147. The clamping dog 157 is provided with a reduced screw threaded end 164 and is adjustable 5 toward and from the confronting face of the rule or strip 95 by means of a nut 165. It is held in adjusted position by the clamp 161. When the lever 162 is rotated, it turns the screw connected to the clamp and draws 10 the clamping members firmly into contact with the shank 160.

Now, it will be manifest that when the rod 144 is drawn downwardly, that the spring 154 will force the vertically reciprocating rod 153 downwardly carrying the lever 152 with it and causing the edge 151 of the clamp member 149 to engage the confronting side surface of the rule 95 and hold it, in co-operation with the end 158 of the 20 dog 157, and prevent its retraction.

The clamping operation of the device just described, for holding the rule 95 in the position in which it is placed by reciprocation of the molding block 90, is such that the 25 clamp members 149 and 158 release the strip or rule prior to the outward movement of the mold block 90 and grip it before its retraction.

When it is desired to remove the mold 30 block 90, it must be taken from the rear end of the housing or molding box 74. To accomplish this, the clamp 161 is opened by rotation of the lever 162, thereupon the dog 157 may be removed, whereupon the molding 35 block may then be moved out of the rear end of the molding box 74.

The strip, or rule that is cast in sections, in the manner heretofore described, is to 40 subsequently be cut into given lengths and definitely trimmed at substantially the same time that the given length is severed from the strip. The lengths thus severed may be several times longer than the sections that are cast at each reciprocation of the molding 45 block, and therefore a means must be provided which will operate, or set into operation, the severing and trimming means after a definite given number of reciprocations of the molding block have been made 50 or after a definite series of sections of strips have been cast.

The head 70 is provided with two sockets 166 and 167 to receive two parallel smooth drawn tubes 168 and 169. These tubes are 55 slidable in the sockets but they are held by a clamping arrangement effected by a slot 170 extending between the sockets and an eccentric clamping member 171 operated by the handle 172. When the handle is out- 60 turned, the slot 170 is made narrower thus reducing the diameter of the sockets 166 and 167 and clamping the tubes therein.

The tubes 168 and 169 with the shaft 173 65 extend rearwardly over the bed 20 of the machine. The shaft 173 is supported in one

end of an arm 174 that extends from the head 70. One end of the arm 174 is down-turned to support a shearing knife 176, a member for shearing the strip 95. This knife is stationary and cooperates with a 70 blade 177 carried upon the oscillating arm 178.

An oscillating block 179 has an integral hub 180 that is supported in the bearing 174. The hub 180 is a part of the block 75 179, and the shaft 173 is rotatably fixed in the hub, but is movable axially therein; and the hub and block are the means for oscillating the shaft. A keyway and key or spline and feather 181 goes the full length 80 of the shaft 173 and a set screw, together with the feather 181, secures the cutting arm 178 to the shaft 173.

A ratchet wheel 182, mounted on the frame 72, is rotatable upon its vertical axis 85 183. A spring 184 is located beneath the ratchet wheel, between the rim and the hub, and tends to normally bias the ratchet wheel in one direction so that the latter will automatically be returned to its normal position 90 by the spring, when released. A pin 217 is located in the ratchet wheel 182, on the under surface thereof, in such position as to cause it to strike another pin or stop 218 located in the frame 72 when the spring 184 95 restores the ratchet to normal position. One side of the rim 185 of the ratchet wheel is undercut, as at 186, to provide a means for securing an adjustable block 187 at selected position on the circumference of the wheel. 100 A tapered wedge 188 fits the tapered undercut and is secured to the block 187 by a screw 189. The block is secured to the rim of the wheel at a selected position thereon for a purpose to be hereinafter more fully 105 explained by means of a key 214 mounted in the block 187 and held in engagement with the teeth of the ratchet by means of a spring 215 acting downwardly. A knob 216 provides the means for lifting the key 214 110 out of engagement with the ratchet teeth to permit the entire block to be shifted to any desired position around the circumference of the ratchet.

Pivoted in a horizontal slot of the block 115 179, as at 190, is a lever 191. In the lever is a spring pressed holding dog, or pawl 192, which serves the purpose of preventing the wheels 182 from being rotated anti-clockwise by the spring when the pawl is in 120 contact therewith.

A bell-crank lever 193 is pivoted to the block 179, at 194. On the end 195 of the lever is a spring pressed ratchet pawl 196 held normally in contact with the teeth of 125 the wheel by spring 197. On the other end, 199, of the bell-crank lever is a spring pressed bolt 200, having its inner end, 201, extended a limited distance by a relatively strong spring 202.

It has heretofore been stated that the vertical rod 138 makes one reciprocation to each revolution of the shaft 23. The upper end of the rod 138 is tapered, as at 203, and 5 each time that the rod 138 is raised the tapered part 203 comes in contact with the end 201 of the bolt 200 and oscillates the bell-crank arm 193 on the pivot 194. The spring 205 normally holds the end 201 in 10 contact with the surface of the vertically reciprocating rod 138, so that when the tapered portion 203, of the vertically reciprocating rod 138, strikes the end of the bolt 201 on its upward and downward movement, 15 it oscillates the bell-crank arm 193 on the axis 194, which causes the ratchet pawl 196 to move the wheel 182 the distance of one tooth, and the holding pawl 192 holds the wheel 182 against the effect of the spring 206 which tends to rotate it in the opposite direction.

The lever 191 is yieldingly held in the position shown in Fig. 4 by means of a flat spring 206, which bears against the boundary of the slot 207 in the block 179. After 25 a definite number of reciprocations of the vertically moving rod 138 have been made, the ratchet wheel 182 will have been moved a given number of notches, by the means 30 heretofore described. For each section of strip cast in the machine the ratchet wheel 182 is moved one notch.

To determine the time of movement of the arm 178 to shear the strip 95 the block 187 35 is placed at a selected point upon the rim of the wheel 182. After the wheel 182 has been rotated, in the manner described, a sufficient distance the block 187 strikes the lever 191 and moves it into the position shown 40 in Fig. 4^a, against the resistance of the yielding spring 206. The lever 191 will not be moved beyond this position, however, because the extended end 191' will be stopped in its movement by the reciprocating rod 45 138. The rod, however, has placed in its confronting surface a round block 207' having a slot 208, into which the lever 191 will be moved, as shown in Fig. 6^a. When the block 187 moves the lever 191 into position 50 shown in Fig. 4^a, the extended end 191 will enter the slot 208 in the block 207 and further reciprocation of the rod 138 up and down will move the lever 191 and the block 179 on its axis 180, thereby oscillating the 55 shaft 173 and causing the knife arm 178 to sever the strip 95, that is at the time located between the stationary arm 175 and the oscillating arm 178.

When the arm 191 has been moved into 60 the position shown in Fig. 4^a, in the manner heretofore described, the extended end 198 of the pawl 196 will strike the confronting surface of the lever 191 and raise the front end of the pawl out of the path of the 65 teeth of the wheel 182 and the holding pawl

192 will be withdrawn from its contact with the teeth of the wheel 182, and therefore the spring 184 will rotate the wheel 182 and return it to its normal position, pin 217 in contact with pin 218. From this it will be 70 apparent that the location of the block 187 on the periphery of the wheel 182 will determine the lengths into which the strip or rule 95 is to be cut. When the block 187 is withdrawn from the path of movement 75 of the arm 191, the spring 206 of the arm will return it to its normal position.

When the block 187 is brought into contact with the lever 191 it is apparent that the ratchet 182 cannot be further rotated by the 80 pawl 196, and the next upward stroke of the bar 138 will cause the bolt 200 to be forced backward against the compression of the spring 202, until the further upward movement of the bar 138 brings the slot 208 85 into line with the lever 191, allowing the lever to be forced into the slot by the pressure exerted by the block 187 against its opposite end.

The knife arm 178 is divided into two 90 parts; the arm 210 which carries the knife 177 and the arm 211 which is separated therefrom by the slot 212 and which serves as a means for catching the rule or strip when it is sheared by the knives 176 and 177. 95 A bolt 213 passes through both of these arms and draws them together for the purpose of tightening them on the hub 180.

Mounted on the outer ends of the tubes 168—169 is the bracket 174^a, provided with 100 a downturned arm 175^a carrying a knife 176^a, and the oscillating arm 178^a carries a knife 177^a, and in every respect it is the same sort of arm as that mounted on the inner ends of the tubes 168—169. The bracket 174^a and the knife arm 178^a may be moved axially of the tubes 168 and 169 and of the shaft 173 so as to be located at the proper distance 105 from the knife 177 of the arm 178. The cutter 177^a on the oscillating arm 178^a and the cutter 176^a on the downturned arm 175^a on the outer end of the structure are the means for trimming to exact dimensions the section 110 that is severed from the cast strip by the knives 177 and 176. The arms 178 and 178^a 115 are moved coincidentally by the oscillation of the shaft 173.

A series of fingers 215' are slidable upon the shaft 173 and each finger is secured in 120 selected position by a screw 216'. The object of the fingers is to assist in bodily and laterally moving the sections or lengths severed from the cast strip. As the sections, or lengths from the strip 95, are cut, they are moved laterally and piled against the 125 bracket 218', which is adjustably secured on a platform 219', each of the fingers 215' contributing towards the parallel movement of the strip.

A sight feed oil cup 220' is used to contain 130

- a lubricant that may be fed into the molding chamber to lubricate the path of movement of the molding block and the carriage upon which it is mounted, and further lubricate 5 the interior of the molding chamber to prevent adhesion of the molten metal thereto. The lubricant is fed through a conduit 221 into the end of the housing and flows down the face of the nozzle plate.
- 10 A collar 222 is fixed to the end of the tube 168 to limit the outward movement thereof. When it is desired to remove the mold block of the machine, the lever 219, controlling the eccentric 220 (Fig. 2), is moved to unclamp 15 the tubes 168 and 169, whereupon the tubes are moved outwardly the distance controlled by the collar 222, which distance permits the lower tube 169 to be entirely withdrawn from the bearing 167 and permits the entire 20 structure to be swung pivotally in the bearing 166, carrying with it the cutter arms 175—178—175^a—178^a, shaft 173 and actuating block 179.
- Novel features not claimed in this application 25 are reserved and will be made the subject of another application to be filed later.
- The employment of a melting pot having a nozzle and choker valve to admit and shut off the flow of metal at intervals, permits 30 the contents of the mold chamber to cool and shrink before it is advanced to make way for successive increments, thus avoiding the frictional resistance which is otherwise the cause of breakage of the strip and other 35 trouble.
- This method also permits the introduction of a lubricant into the mold after the strip has been advanced and before the next succeeding cast to further assist its removal and 40 prevent adhesion.
- By arranging the molding chamber in axial alignment with the metal pot nozzle, the molten metal is introduced into the molding chamber with the least possible interference 45 to its flow, thus causing the incoming fluid metal to impinge upon the solidified edge of the previously formed casting with great force, causing them to fuse together and form an integral unit of considerable 50 strength.
- By introducing the molten metal into the molding chamber in a direction which will permit the incoming metal to strike the entire edge of the previously formed and solidified casting simultaneously and in the direction of its length, the fluid metal is caused to fuse deeply into the previously formed casting, making a homogeneous strip with no weakness at the joints.
- 55 By causing the incoming fluid metal to impinge upon the previously formed casting with great force and simultaneously strike the entire edge of same, in the direction of its length, high temperatures of the
- metal and casting box are avoided. This 65 important advantage will be further appreciated when using metals for casting printers' leads, slugs and rules, which usually carry a considerable percentage of tin, having a low fusing point, and which ingredient 70 is readily damaged by high temperatures.
- Other uses to which my apparatus may be applied will be evident to those skilled in the art to which this appertains, such as the casting of tubular or round shaped bars as well 75 as rectangular shapes, and wherever in the specification and claims strips or bars are referred to, I do not desire the meaning to be limited to any particular cross-sectional configuration.
- Having described my invention what I claim as new and desire to secure by Letters Patent is:—
1. A device for cutting strips of material into sections of definite length, the combination, of a cutting and trimming mechanism; an intermittently moving means for operating said mechanism; a ratchet operated by said intermittently moving means, and means operated at a predetermined time 80 by said ratchet to connect said intermittently moving means to said cutting mechanism.
2. In a device for cutting strips of material into sections of definite length, the combination, of means for intermittently advancing the strip to be severed; a cutting and trimming mechanism; an intermittently moving means for operating said mechanism normally disconnected from said mechanism; a ratchet operated by said intermittently moving means, and means operated at a predetermined time by said ratchet to connect said intermittently moving means to 85 said cutting mechanism.
3. In a device for cutting strips of material into sections of definite length, the combination of means for intermittently advancing the strip to be severed; a cutting and trimming mechanism, operable during 90 a dwell between movements of said strip; an intermittently moving means for operating said mechanism normally disconnected from said mechanism; a ratchet operated by said intermittently moving means and means operated at a predetermined time by 95 said ratchet to connect said intermittently moving means to said mechanism, and means for adjusting said connecting means to vary 100 the time of its operation.
4. In a device for severing strips of material into sections of predetermined length, means for severing the strip into sections; means for trimming the opposite end of each section while the strip is being severed, and 110 means for adjusting the distance of separation between the severing and the trimming means.

5. In a device for severing strips of material into sections of definite length, cutting members adjustable with respect to each other adapted to operate on both ends of said sections simultaneously and means for severing the sections from the strip and simultaneously trimming the opposite end of said section.
6. In a device for cutting strips of material into sections of predetermined length, means for advancing the material to be severed, means independent of the strip for operating the severing means at predetermined intervals, and means adjustable with respect to the severing means for coinciden-
- 5 tally trimming the strip to exact linear dimensions.
7. In a device for cutting intermittently moving strips of material molded into sections of definite length, comprising a plurality of pairs of spaced-apart relatively adjustable cutters adapted to be operated by a common member to simultaneously sever and trim the sections and operable in timed relation with the movement of the strips.

In testimony whereof I hereunto subscribe my name.

JOHN S. THOMPSON.
